UNITED STATES PATENT OFFICE.

SETH S. GETCHELL, OF WOONSOCKET, RHODE ISLAND, ASSIGNOR TO GEORGE DRAPER & SONS.

OIL-CAN.

SPECIFICATION forming part of Letters Patent No. 299,469, dated May 27, 1884.

Application filed March 14, 1884. (No model.)

To all whom it may concern:

Be it known that I, SETH S. GETCHELL, of Woonsocket, county of Providence, State of Rhode Island, have invented an Improvement 5 in Oil-Cans, of which the following description, in connection with the accompanying drawings, is a specification, like letters on the drawings representing like parts.

This invention is an improvement upon that 10 class of oil-cans containing an air-eduction and air-induction pipes suspended within the can from a collar. In this class of can I have provided the air-eduction pipe with a bottom-closing device, (shown as a removable cap or 15 plug,) to enable access to be had to the interior of and cleanse the said pipe when necessary.

Figure 1 is a central vertical section of an oil-can containing my invention, the spout being partially broken off. Fig. 2 is a top view 20 of the can, the spout being omitted; and Fig. 3 is a section of Fig. 1 on the dotted line *x x*.

The body A of the can, which may be of any usual or suitable construction, is provided at its upper end with a screw-threaded ring, *a*, 25 to receive the exteriorly-screw-threaded collar or neck B, the latter being provided with a throat or opening, *b*, to permit the can to be supplied with oil, the said throat having preferably a screw-thread to enable a spout, *s*, 30 (partially shown,) to be connected therewith. The collar, perforated at *b*², has an air-induction pipe or tube, *c*, secured to its under side, the said inductive pipe opening into or communicating with an air-eduction tube or pipe, 35 *c'*, the open upper end of which is located under the lower end of the said collar, at one side of its central opening, *b*, or out of line there-

with, so that oil being poured into the can cannot enter the mouth of the said tube or pipe to clog the same and prevent the free flow of 40 air therefrom into the body of the can whenever oil is being poured therefrom. The air-chamber, composed of the pipes *c c'*, being connected with the removable collar or neck B, must be of a size to permit it to pass through 45 the ring *a*, in order that said air-chamber may be withdrawn from can after unscrewing the neck from said collar, and when so withdrawn the cap or cover *d* at the lower end of the tube *c'* may be readily removed from the bottom 50 of the chamber to permit the interior of said chamber to be cleansed, should it have become clogged in any manner.

Instead of the cap, I may stop the lower end of the tube *c'* by a plug, as shown in dotted 55 lines, Fig. 1.

I claim—

The body A, its attached threaded ring, and the threaded collar secured therein, and provided with the openings *b b*², combined with 60 an induction and eduction pipes, constituting an air-chamber in connection with and made removable from the body A, with the said collar or neck, the air-chamber having a removable bottom-closing device, to operate substantially as described.

In testimony whereof I have signed my name to this specification in the presence of two subscribing witnesses.

SETH S. GETCHELL.
